COMMUNICATION SYSTEM

Irving A. Krause, Jersey City, N. J., assignor to
 Federal Telephone and Radio Corporation,
 New York, N. Y., a corporation of Delaware

Application April 20, 1944, Serial No. 531,859

20 Claims. (Cl. 250—6)

1

The present invention relates to communication systems and more particularly to a communication system having means for preventing or rendering more difficult unauthorized reception of the transmitted intelligence.

One object of the invention is to provide a method and means for modulating a pulse sub-carrier so that the modulating intelligence will be undetectable by the usual receiving apparatus; and

Another object of the invention is to provide a method and means for receiving and detecting such modulated pulses, and for minimizing interference.

One of the features of the invention is to provide means for generating a train of pulses constituting a sub-carrier wave, modulating, either by amplitude, time or other pulse characteristic, the odd pulses of the train out of phase with the even pulses by a signal wave representing the intelligence which it is desired to transmit, and recombining the modulated pulses in the order of their generation. At a receiving point, the modulated pulses are separated according to odd and even pulses, whereupon at least one of the groups of separated pulses is detected.

An additional feature of the invention comprises providing means for receiving the modulated pulses at a point remote from the transmission thereof, separating the odd group of pulses from the even group, demodulating and/or filtering to obtain the audio wave defined thereby, shifting the phase of one of the waves by an amount sufficient for recombining with the other wave, and reproducing the intelligence thereof.

A further feature of the invention is to provide, in addition to the different phase modulation of the odd and even pulses, a further modulating energy in the form of a "masking" wave, this additional energy being applied in a manner to the odd and even pulses so that by inversion and mixing or direct mixing of the two audio waves produced from the odd and even pulses, as the case may be, the "masking wave" is removed from the desired intelligence wave.

Other objects and features of the invention will be apparent from the following description of a preferred form of the invention and from the drawings, in which:

Fig. 1 is a circuit diagram of a preferred form of transmitter embodying the present invention;

Fig. 2 is a set of curves used in explaining the operation of the circuit of Fig. 1;

Fig. 3 is a circuit diagram of a preferred form of receiver embodying the present invention;

2

Fig. 4 is a circuit diagram of a modified form of transmitter embodying the present invention;

Fig. 5 is an alternative form of demodulator for use in the circuit of Fig. 3; and

Fig. 6 is a graphical illustration used in explaining the operation of the demodulator of Fig. 5.

For the purpose of illustrating my invention, I have shown in Figs. 1 to 3 the principles thereof by means of amplitude modulation. In Fig. 1 is shown a generator 4 having a substantially sine wave output such as indicated by the waveform 6. This wave 6 is of sub-carrier frequency, that is, lower than the frequency of the usual R. F. or ultra high frequency carrier wave but higher than that of an audio signal.

A known wave shaper 8 translates the sine wave 6 into a substantially square wave 10. A known wave inverter 12 inverts by 180° the square wave 10 as indicated by square wave 14. The shaper 8 and inverter 12, of course, may be replaced by a multivibrator circuit wherein square waves of opposite polarity may be obtained.

The outputs of wave shaper 8 and inverter 12 are fed to two differentiators 16 and 18, respectively, of the character adapted to translate each square pulse portion of the waves 10 and 14 into two sets of narrow width positive and negative pulses, as indicated at 20 and 22, respectively. The pulses 20 and 22 are applied to two tetrodes where the negative pulses are eliminated and the positive pulses are amplitude modulated. This is accomplished by biasing each of the two tetrodes V₁ and V₂ to cut-off. V₁ conducts only the positive pulses of wave 20 and V₂ conducts only the positive pulses of wave 22. Since the positive pulses of wave 20 alternate with the positive pulses of wave 22, the pulses conducted by V₁ will be termed the "odd" pulses, and the pulses conducted by V₂ the "even" pulses.

The screen grids 24 and 26 of tubes V₁ and V₂ are respectively connected to opposite ends of the secondary coil of a transformer 28. The primary of transformer 28 is connected to a source of audio signals representing the intelligence which it is desired to transmit. It will be seen that due to the opposite polarity existing at the ends of the transformer secondary, screen grids 24 and 26 will be energized 180° out of phase by the audio input. Since V₁ conducts only odd pulses and V₂ conducts only even pulses, the odd pulses and the even pulses will be audio modulated 180° out of phase to one another. The waveforms 30 and 32, respectively representing

the outputs of V_1 and V_2 , will thus have different amplitudes depending on the characteristics of the modulating signal applied to transformer 28.

The outputs of tubes V_1 and V_2 are combined at 34 across resistor R , the combined pulse energy being represented by waveform 36. This wave 36 is then fed to an R.-F. translator 38 where the audio pulses are amplified and transformed into R.-F. pulses at a given carrier frequency for transmission from antenna 40.

In addition to the mixing of the two groups of pulses modulated 180° out-of-phase, the pulses may be further modulated by a given "masking" signal, the further modulation being added to the pulse output from tubes V_1 and V_2 in proper phase relation according to the time spacing of successive pulses. This further modulation may take the form of a saw-tooth wave 42 from source 43 applied to the mid-point of the secondary winding of transformer 28 by connection 44. The saw-tooth voltage wave 42 thereby energizes both screen grids 24 and 26 in phase, as contrasted to the out-of-phase energization of these grids by the audio signal input taken across the ends of the transformer secondary winding.

To summarize the operation of the transmitter circuit of Fig. 1, reference is now made to the curves of Fig. 2. Curves *a* and *b* illustrate the pulse outputs 30 and 32 of tubes V_1 and V_2 , respectively, in the absence of any modulation. An audio modulating signal is shown in curve *c*, the solid line 45 representing the voltage at one end of the secondary winding of transformer 28, and the broken line 47 representing the voltage at the other end of the winding.

The effects of the modulating wave *c* on the pulses of curves *a* and *b* are shown in curves *d* and *e*, respectively. The resulting wave 36 appearing at point 34 is represented by curve *f*. The in-phase "masking" wave 42 is shown in *g*, and its effect on the output wave *f* is shown in *h*, both odd and even pulses being modulated in phase in the order of their generation as explained above. While the pulses of the curves of Fig. 2 have all been drawn as being of positive polarity, it will be understood that their actual polarity according to the circuit of Fig. 1 will be as indicated at the different points in the circuit. The masking wave 42 may be regarded as having the same effect on the transmitted pulses as a non-pulse interference signal such, for example, as an amplitude modulated carrier.

A form of receiver according to the present invention is shown in Fig. 3. The energy transmitted from antenna 40 of Fig. 1, after being received on antenna 46, is passed through detector 48. The detector 48 demodulates the R.-F. carrier energy supplied by translator 38 into a series of sub-carrier pulses substantially identical to the pulse train 36 of Figs. 1 and 2. Receiving the pulse output of detector 48 are a first keyer 50, a second keyer 52 and a timer circuit 54. Keyer 50 handles only the odd pulses of the train while keyer 52 handles only the even pulses. Keyer 50, keyer 52 and timer 54 each include an electron discharge tube biased to cut-off as illustrated.

By providing the timer 54 with a plate circuit 56 tuned to the recurrence frequency of the pulse train 36 (curves *f* and *h*, Fig. 2), the received pulses will be passed through a circuit 58 to the grid of a triode 60 constituting one element of a multivibrator 62. Multivibrator 62 is provided with a second triode 64, the grids and plates of the two tubes being cross-connected in normal manner.

Multivibrator 62 is adjusted to operate at one-half the pulse rate, the pulses received on the grid of triode 60 over circuit 58 serving to key the operation of the multivibrator at one-half the recurrence frequency.

As is well known in the art, a multivibrator may be used to "trigger" or "deblock" other circuits according to its rectangular wave output. If the time constants of the multivibrator are selected to produce a substantially square wave, then the plate circuits of the multivibrator tubes will be of alternately positive and negative potential for substantially equal periods of time. The two plate circuits of the multivibrator 62 are connected to screen grids 66 and 68 in the electron discharge devices of the first keyer circuit 58 and the second keyer circuit 52, respectively. The screen grid 66 in the first keyer tube 78, is alternately driven positive and negative at the rate of operation of the multivibrator. The same cycle of operation applies to the screen grid 68 of the second keyer tube 72, except that when grid 66 is driven positively the grid 68 is driven negatively and vice versa.

Consider now the pulses received by the control grid 74 of the first keyer tube 78. Odd pulses appearing on the grid 74 in coincidence with the positive potential conditions of grid 66 act to make the tube 78 conductive. When the following even pulse appears on the grid 74, the screen grid 66 having been driven negative by the action of multivibrator 62, the tube remains at cut-off thereby blocking the even pulse.

The reverse action occurs in the second keyer circuit 52. Since one plate circuit of multivibrator 62 is positive when the other plate circuit is negative, the polarity of screen grid 68 will always be opposite in polarity to the polarity of screen grid 66. Tube 72 will therefore conduct the even pulses and block the odd pulses.

A pair of resistance-condenser combinations 82 and 84 form parts of the plate circuits of keyers 58 and 52, respectively. The elements of these combinations 82 and 84 are chosen of such values that the time constants of the combinations operate to filter out the pulses, thereby reproducing with a minimum of distortion the audio envelope wave representing the intelligence applied to the primary of transformer 28 of Fig. 1.

Since the audio wave of the odd pulses passed by keyer 50 is 180° out of phase with the audio wave of the even pulses passed by keyer 52, the audio waves reproduced by the two keyer circuits at their output connections 75 and 77 are 180° out of phase. By applying the output wave of one of the keyers, such as 52, to a phase inverter 76 for 180° inversion and then combining the inverted wave output by connection 78 to the wave of output connection 75, a more accurate reproduction of the intelligence wave is effected than that represented by the separate outputs of keyer circuits 50 and 52. The combined audio wave is then amplified at 79 and applied to speaker 80.

It should be noted that either of the audio waves appearing in the plate circuits of keyers 50 and 52 defines the transmitted intelligence. The purpose of mixing the two audio waves is to reproduce the intelligence to a higher degree of accuracy than is possible through the utilization of either wave alone. The output of one of the keyer circuits may, of course, be applied directly to amplifier 78 and subsequently reproduced. This would dispense with the necessity of employing a second keyer circuit, although as previously

mentioned, accuracy of definition would be sacrificed to a certain degree.

In cases where the "masking" signal 42 is utilized, or an interference signal, such as an A. M. modulated carrier, both keyer circuits 50 and 52 must be employed. The reason for this is that the masking signal and/or interference signal present on the same carrier, as the case may be, is applied in phase to both odd and even pulses. If now the even pulse envelope wave is phase inverted in the receiver by inverting circuit 76, the mixing of the two envelopes in amplifier 78 will cancel out the masking signal and any such interference signal leaving only the audio modulation representing the desired intelligence.

It will be obvious that the masking signal 42 may itself represent intelligence. In such an event the odd and even envelope waves may be mixed directly by moving switch contact 85 from contact 86 to contact 87 thereby bypassing phase inverter 76. This would cancel the signals applied to the pulses through the primary of transformer 28, Fig. 1, leaving the signal applied to the center tap of the secondary of the transformer 28. Thus, either of the modulating input signals of Fig. 1 may carry the actual message, or, if desired, they may represent separate messages. Where the signal 42 is the desired intelligence, then interference minimizing must be carried out by a suitable blocking arrangement.

In Figs. 4, 5 and 6 I have shown the principles of my invention by way of time modulation. Fig. 4 illustrates a P. T. M. (pulse time modulation) transmitter including a generator 100 for producing a base wave 102. The output of generator 100 is fed both to a 90° phase shifter 104 and to one primary winding 105 of a transformer 106. The output of phase shifter 104 is fed to one primary winding 107 of a second transformer 108 which is similar to transformer 106.

Transformer 106 constitutes part of a T. M. modulator 110. Also included in the modulator 110 is a pair of electron discharge tubes 112 and 114 connected together in push-pull fashion, the grids of tubes 112 and 114 being fed from opposite ends of the split secondary winding 109, 111 of transformer 106. The anode circuits of tubes 112 and 114 are joined together at 116 and the combined outputs of the tubes fed to a pulse clipper and shaper 118. Transformer 108 constitutes part of a second T. M. modulator 120 which is similar to modulator 110.

Also shown in Fig. 4 is a transformer 28a which may be identical to the transformer 28 in Fig. 1. The ends of the secondary winding of transformer 28a are connected respectively to a second primary winding 122 of transformer 106 and to a second primary winding 124 of transformer 108. The audio-signal representing the intelligence which it is desired to transmit is applied to the primary winding of transformer 28a in the same manner that the audio-signal is applied to the primary winding of transformer 28 of Fig. 1. A masking signal 42 which may be identical to the masking signal of Fig. 1 is applied to the center-tapped secondary of transformer 28a similarly as shown in Fig. 1. The combined TM outputs of modulators 110 and 120 are fed to an R. F. translator 130 and then transmitted from an antenna 132.

Referring particularly to the modulator circuit 110, it will be understood that it amplifies and, in effect, full-wave rectifies the wave 102, to obtain a cusper wave 113. Time modulation of the cusper wave is produced by applying the

signal intelligence to primary coil 122 of the transformer 106. The signal intelligence operates, in effect, to vary the wave 102 relative to its zero axis as regards the full-wave rectification. This relative variation between the wave and the zero axis thereof is illustrated by the upper and lower modulation limits 102a and 102b. When the input signal varies the relative relation between the zero axis and the wave 102 as indicated by limit 102a, the cusper wave is displaced as shown by the broken line 113a, and when displaced to the opposite limit 102b by broken line 113b. It will be observed that the signal wave varies the cusps 133, 134, 135 and 136 in push-pull manner toward and away from each other thereby successively decreasing and increasing the time interval between successive cusps.

For transmission purposes, the cusps are preferably clipped from the wave by a known clipper and shaper 118 and shaped to form a train of substantially narrow width pulses 138.

The TM pulse output from modulator 120 will be a train of pulses similar to the pulse train 138, but due to the action of phase shifter 104 the pulses from modulator 120 will be out of phase with the pulses from modulator 110 similarly as in the case of pulse trains 30 and 32 of curves a and b, Fig. 1. Thus when these pulse trains are combined for application to translator 130, the pulses from modulator 120 will alternate with the pulses from modulator 110.

When a TM transmitting system such as shown in Fig. 4 is employed, means must be provided in the receiver for demodulating these TM pulses. Fig. 5 illustrates a TM demodulator 82a which may be incorporated in the receiving circuit of Fig. 3 to replace the pulse amplitude demodulating or filter circuits 82 and 84. The odd TM pulses (such as the train of TM pulses 138 of Figs. 4 and 6, for example) passed by the keyer tube 70 across resistor 70a are applied over a connection 140 to a frequency selector 142 which serves to shock-excite a high "Q" circuit 144 to produce a continuous wave 146, Fig. 6, which preferably is an even harmonic of the base wave 102 produced by the generator 100 of Fig. 4. The wave 146, however, is preferably of a frequency which corresponds to the pulse repetition rate.

Curve a of Fig. 6 represents a short train of pulses 138 time modulated according to a substantially linearly increasing signal wave. Curve b shows a wave 146 in timed relation to the pulses 138 and a fundamental wave 148 which is obtained from wave 146 by means of a frequency divider 150 which is inductively coupled to the circuit 144. The wave 148 is called a "fundamental wave" because the period thereof corresponds to the pulse cadence period between alternate pulses as indicated at T on curve a of Fig. 6.

Either the initial wave 146 or the fundamental wave 148 may be used for demodulation purposes, but an odd harmonic of the fundamental wave 148 is preferred. The fundamental wave 148, therefore, is applied to a frequency multiplier 152 whereby a desired odd harmonic wave 154, curve c, is obtained. While wave 154 is shown for purposes of illustration to be the third harmonic of the wave 148, a higher odd harmonic may be preferred in some cases.

A phase shifter 156 is provided in the output of the frequency multiplier to shift the demodulating wave in phase with respect to the TM pulses. The demodulating wave 154 is applied directly to a mixer unit 158 for translation of the

time displacement of the pulses into amplitude displacement.

The TM pulses 138 are applied to the unit 158 through an amplifier 160. The intelligence signals conveyed by the TM pulses are passed from the output 162 of the unit 158 through a low-pass filter 164 to the output lead 75 for reproduction in conjunction with the intelligence wave of the other branch the same as in Fig. 3.

Assuming that the sine wave 154 is used as the demodulating wave, the sine wave will be applied to the screen grid 165 of the vacuum 166. The tube is self-biased by a resistance-capacitance circuit 168. The main grid 170 is connected through coupling condenser 172 to the outlet connection 174 of the amplifier 160. The plate 176 is provided with a load resistor 178 from which connection 162 is applied to the low-pass filter 164.

The self-bias of the tube 166 is such that it will not respond to the input potential of the wave 154, but will respond to the energy of the TM pulses superimposed upon the wave 154. That is to say, the tube produces a pulse output in its plate circuit whenever the combined energy of wave 154 and pulses 138 exceeds a given clipping level 180. Thus, pulses are produced at the output connection 162 which vary in amplitude according to the position of the TM pulses on the inclined portions of the wave 154. When the pulses are modulated toward each other as indicated by the arrows on the curve *a* of Fig. 6, the amplitude of the output pulses is increased. When the displacement modulation of the pulses is in directions away from each other the amplitude of the output pulses decreases.

This amplitude modulated pulse output, as indicated at curve *d*, provides a signal wave 182 in the output of the low-pass filter 164, the pulse portions defining the envelope of the signal wave 182 being removed by the filter.

In place of the even-pulse amplitude-demodulating circuit 84 of Fig. 3 is substituted a second TM demodulating circuit which is similar in all respects to the TM demodulating circuit 82a. The output of this second demodulating circuit is fed through conductor 77 to switch 85.

While I have described above the principles of my invention in combination with specific apparatus for amplitude and time modulation of pulses, it is to be clearly understood that this description is made only by way of an example of several applications of the principles of my invention, and not as a limitation of my invention and the scope of the accompanying claims.

I claim:

1. A method of modulating a train of pulses of electrical potential comprising modulating a given characteristic of the odd pulses of said train with a given signal energy and modulating a like characteristic of the even pulses of said train with said given signal energy shifted in phase 180° from the signal energy applied to said odd pulses.

2. The method according to claim 1 wherein the modulating operations of the odd and even pulses comprise varying the amplitude of the pulses according to the respective modulating signal energy.

3. The method according to claim 1 wherein the modulating operations of the odd and even pulses comprise displacing the pulses in time position according to the respective modulating signal energy.

4. A method of pulse modulation comprising

producing two series of pulses of electrical potential, the pulses of one series alternating with the pulses of the other series, modulating the pulses of said one series with signal energy, modulating the pulses of said other series with said signal energy displaced in phase substantially 180°, and combining the pulses of said two series into a single train of pulses.

5. A method of pulse modulation comprising producing two series of pulses of electrical potential, the pulses of one series alternating with the pulses of the other series, modulating a given characteristic of the pulses of said one series according to a given signal energy, modulating said given characteristic of the pulses of said other series with said given signal energy shifted substantially 180° out of phase with the signal energy applied to said one series, and modulating said given characteristic of the pulses of both series with a further signal energy.

6. A method of private communication comprising generating two series of pulses of electrical potential, the pulses of one series alternating with the pulses of the other series, modulating a characteristic of the pulses of one series with a given signal energy, modulating a like characteristic of the pulses of the other series with said given signal energy shifted substantially 180° out of phase with the signal energy applied to said one series, combining the pulses of both series into a train, transmitting said train of pulses, receiving said train of pulses at a receiving point, separating the two series of pulses, and demodulating the pulses in at least one of the two series to reproduce said signal energy.

7. A method according to claim 6 further including demodulating the pulses of the other of the two series, shifting in phase 180° the signal energy obtained from one of said two series, and combining the phase shifted signal energy with the signal energy obtained from the other of said two series.

8. A method of private communication comprising generating two series of pulses of electrical potential, the pulses of one series alternating in time with the pulses of the other series, modulating a given characteristic of the pulses of said one series according to a given signal energy, modulating said given characteristic of the pulses of said other series with said given signal energy shifted substantially 180° out of phase with the signal energy applied to said one series, modulating both series of pulses with a further signal energy, combining the pulses of both series into a single train, transmitting said train of pulses, receiving said train of pulses at a receiving point, separating the two series of pulses, demodulating to audio waves the pulses of the two series, shifting 180° in phase the audio wave derived from one of said series, combining said phase shifted audio wave with the other audio wave to cancel out said further signal, and reproducing the intelligence of said given signal energy from the combined audio wave.

9. A method of private communication comprising generating two series of pulses of electrical potential, the pulses of one series alternating in time with the pulses of the other series, modulating a given characteristic of the pulses of said one series according to a given signal energy, modulating said given characteristic of the pulses of said other series with said given signal energy shifted substantially 180° out of phase with the signal energy applied to said one series, modulating both series of pulses with a further

signal energy, combining the pulses of both series into a single train, transmitting said train of pulses, receiving said train of pulses at a receiving point, separating the two series of pulses, demodulating to audio waves the pulses of the two series, combining the audio waves derived from the two series to cancel out said given signal energy leaving said further signal energy, and reproducing the intelligence of said further signal energy.

10. A method of reproducing the intelligence of a given signal energy from a train of pulses of electrical potential wherein the odd pulses are modulated with said energy and the even pulses are modulated with the same energy shifted 180° in phase; comprising separating the odd pulses from the even pulses, demodulating to audio waves the signal energy with which pulses of the two series are modulated, shifting 180° in phase one of the audio waves, combining the phase shifted audio wave with the other audio wave, and reproducing the intelligence of the combined audio waves.

11. A method of reproducing the intelligence of a given signal energy from a train of pulses of electrical potential wherein the odd pulses are modulated with said energy, the even pulses are modulated with the same energy shifted 180° in phase and both odd and even pulses are further modulated by an undesired signal energy; comprising separating the odd pulses from the even pulses, demodulating to audio waves the signal energy with which pulses of the two series are modulated, shifting 180° in phase one of the audio waves, combining the phase shifted audio wave with the other audio wave to cancel out said undesired signal energy, and reproducing the intelligence of said given signal energy from the combined audio waves.

12. A modulator system comprising means for producing a train of pulses of electrical potential, means to modulate a given characteristic of the odd pulses with a given signal energy, and means to modulate said given characteristic of the even pulses with said given signal energy shifted in phase 180° from the signal energy applied to the odd pulses.

13. A system according to claim 12 wherein the two modulating means are arranged to vary the amplitude of the pulses according to the instantaneous value of the respective modulating signal energy.

14. A system according to claim 12 wherein the two modulating means are arranged to displace the time position of the pulses according to the instantaneous value of the respective modulating signal energy.

15. A pulse modulating system comprising means for producing two series of pulses of electrical potential, the pulses of one series alternating with the pulses of the other series, modulator means for the pulses of said one series, modulator means for the pulses of the other of said series, a source of signal energy, means to apply said signal energy at 180° difference in phase to the two modulator means, and means for combining the pulse output of the two modulator means into a single train of pulses.

16. A system according to claim 15 wherein said means for applying energy to said two modulator means includes means for applying a further

signal energy in phase to the two modulator means.

17. A private communication system comprising means for producing a train of pulses of electrical potential, means to modulate a given characteristic of the odd pulses with a given signal energy, means to modulate the even pulses with said given signal energy shifted in phase 180° from the signal energy applied to the odd pulses, means for transmitting the train of pulses thus modulated, means for receiving said train of pulses at a receiving point, means for separating the odd pulses from the even pulses, and means for demodulating one of the series of pulses from said separating means to reproduce said given signal energy.

18. A system for reproducing the intelligence of a given signal from a train of pulses of electrical potential wherein the odd and even pulses are modulated with said energy at 180° difference in phase; comprising means for separating the odd pulses from the even pulses, means for demodulating to audio waves the intelligence with which the odd and even pulses are modulated, means for shifting 180° in phase one of the audio waves, means for combining the phase shifted audio wave with the other audio wave, and means for reproducing the intelligence of the combined audio waves.

19. A system for reproducing the intelligence of a given signal energy from a train of pulses of electrical potential wherein the odd and even pulses are modulated with said energy at 180° difference in phase, and further modulated with an undesired signal energy in phase with respect to the odd and even pulses; comprising means for separating the odd pulses from the even pulses, means for demodulating to audio waves the intelligence with which the odd and even pulses are modulated, means for shifting 180° in phase one of the audio waves, means for combining the phase shifted audio wave with the other audio wave to cancel out said undesired signal energy, and means reproducing the intelligence of said given signal energy from the combined audio waves.

20. A system for reproducing the intelligence of a given signal energy from a train of pulses of electrical potential wherein the odd and even pulses are modulated with said energy at 180° difference in phase, and further modulated with a further signal energy in phase with respect to the odd and even pulses; comprising means for separating the odd pulses from the even pulses, means for demodulating to audio waves the intelligence with which the odd and even pulses are modulated, means for combining the two audio waves to cancel out said given signal energy, and means for reproducing the intelligence of said further signal energy from the combined audio waves.
